UNITED STATES PATENT OFFICE

2,691,419

PROPELLER

Charles Andersen, New York, N. Y.

Application March 10, 1950, Serial No. 148,987

1 Claim. (Cl. 170—165)

1

My invention relates to propellers for imparting motion to boats or vessels in a fluid medium. More particularly my invention pertains to propellers especially adapted for imparting motion to marine craft. Generally my inventive idea is applicable to propellers whether employed for imparting motion to a craft or for imparting motion to a fluid in which the propeller is operating.

Among the objects of my invention is to provide a propeller that may be economically operated at high efficiency. It is also an object to provide a substantially non-cavitating propeller capable of exerting a powerful thrust. Further objects and the unique advantages of my invention will be brought out as the following specification is read in conjunction with the drawings forming a part of this application, in which:

Figure 1 is a front elevation of a propeller embodying my invention.

Figure 2 is a side elevation of Fig. 1, partly in section, on line 2—2 of Fig. 1.

Figure 3 is a series of profile sections of a blade of a propeller made according to my invention taken on the lines A—A, B—B, C—C and D—D.

Figure 4 is a series of profile sections of another blade of my propeller taken on the lines E—E, F—F, G—G and H—H.

Referring to Fig. 1 of the drawing 5 are the blades of the outboard or first propeller, and 6, 6 are the blades of the inboard or second propeller. It will be noted that both propellers are carried by a single sleeve 7 and that one set of blades 6, 6 is set at an angle of about 30 degrees in advance of the blades 5, 5 of the other. Obviously in place of the single sleeve 7, each propeller, complete with its own sleeve, may be constructed independently and thereby readily set at an appropriate relative angle. A purpose of the two propellers, set one behind the other and having their blades suitably profiled, is to develop the utmost effective power from the motive force imparted to it and to reduce to a minimum the amount of slip and drag. As indicated by the series of profiles (Fig. 3) the blades of the outboard propeller 5 may be formed in the usual manner, the outer surface being slightly convex and the under surface being dished or concave so that in operating relative to a fluid medium a screw-like path is described. The inboard propeller however, which is set away from the other propeller a predetermined distance, as indicated in Fig. 4 preferably is formed to provide a different set of blade profiles i. e.: the outer faces of same being substantially flat and tapered in cross section, the entering edge being relatively thin. By the means

2

described, when rotation occurs as indicated at 17, the fluid engaged by the inboard blades 6 is passed without substantial turbulence into the bite of the blades of the outboard propeller 5, where, due to the form of the blade profile the initial thrust of the outboard propeller is not only maintained but substantially augmented and accelerated. In the disclosure but two propellers are shown and discussed but it should be understood that the novel principle herein described may be applied to more than two tandem propellers suitably spaced apart and angularly set relative to each other. While the full benefit of the invention is best realized when the propellers are driving in their intended direction the system may be operated in the reverse direction. In a marine application, for example when going ahead, water forced off the driving faces of the blades 16 of the inboard propeller 6 is driven to the back side of the blades 15 of the outboard propeller 5, thereby increasing the overall thrust of the unit and increasing the driving speed or propulsion travel rate. In Fig. 2, the sleeve 7 carrying the propeller blades 5 and 6, is shown as having a tapered bore 8 fitted to a similarly tapered portion 9 of a shaft 10, carried in a suitable bearing 11, the sleeve 7 being secured upon the tapered portion of the shaft by means of a nut 12 screwed onto the threaded portion 13 of the shaft 10 and covered by the cap 14. As may be noted in the views, the leading edges of blades 5, 5, etc., are indicated at 15, 15, while the leading edges of the other blades 6, 6, etc., are noted 16, 16, inasmuch as the normal rotation of the propellers occurs in the direction indicated in Figure 1 by arrow 17. Having described and illustrated a preferred embodiment of my invention what I claim as new is:

40 In a propeller system, a first or outboard propeller mounted upon a drive shaft, said first propeller consisting of three identical blades, said blades being equi-angularly spaced from each other, each of said blades having concave driving surfaces and convexly curved back surfaces, a second or inboard propeller mounted upon the same drive shaft as said first propeller, said first and second propellers being spaced apart and positioned in tandem, the said second propeller consisting of three identical blades, said last mentioned blades of the second propeller being equi-angularly spaced from each other, each of said latter blades having flat driving surfaces and flat back surfaces, said blades being tapered from their front edge to their rear edge on said back surfaces, said second propeller being spaced angu-

3

larly behind said first propeller whereby to provide a space to allow water to go through, both of said propellers being of substantially the same diameter.
